UNITED STATES PATENT OFFICE.

HEINRICH TÜRK, OF BALTIMORE, MARYLAND, ASSIGNOR TO THE PORCELAIN ENAMEL AND MANUFACTURING COMPANY, OF BALTIMORE, MARYLAND, A CORPORATION OF MARYLAND.

DOOR-OPERATING DEVICE.

1,253,996.

Specification of Letters Patent. Patented Jan. 15, 1918.

Application filed January 17, 1917. Serial No. 142,884.

To all whom it may concern:

Be it known that I, HEINRICH TÜRK, a citizen of the United States, residing at Baltimore, State of Maryland, have invented 5 new and useful Improvements in Door-Operating Devices, of which the following is a specification.

This invention is an improved device for operating the doors of furnaces and the like.

10 In the operation of enamel furnaces, it is common practice to have a lever immediately above the muffle furnace door, and attached to said door, an extra operator being required to manipulate the said lever, and 15 thereby control the door, while another operator is employed in depositing the ware into the furnace. One of the objects of the invention is to improve upon the above described conditions, by providing means 20 whereby the movements of the door may be controlled by the operator who is handling the material to be placed into or removed from the furnace, thereby avoiding the necessity of an additional man to operate the 25 door. A further object is to provide means whereby the door may be held open while the operator is moving toward or away from the furnace, such means being so constructed that the operator may release the door at 30 any time.

The invention will be hereinafter fully set forth and particularly pointed out in the claims.

In the accompanying drawing, the figure 35 is a side elevation illustrating the invention.

Referring to the drawing, 10 designates a furnace of any desired design, conventionally illustrated, provided with a door 11, 40 slidably mounted in suitable manner so as to normally close by gravity. Attached to the top of the door is a cable 12 passed over sheaves 13, and connected to a counter-weight 14.

45 Pivots anchored to the floor of the room in which the furnace is located, as indicated at 15, is a running board 16, the pivotal connection being at one end of the board, the other end of the board being connected 50 by a cable 17 with the door 11, said cable passing over sheaves 18. The door is counterbalanced partly by the weight of the running board, but is mainly counterbalanced by the weight 14. In order to pro- 55 vide for adjustment of the distance to which

the door is to be opened, a turnbuckle 19, is provided, as shown. In the drawing, the operator is shown as in the act of stepping upon the running board, to insert the fork 21, mounted upon the track 22, into the fur- 60 nace.

In practice, when the operator desires to deposit the ware into the furnace, or to remove the ware therefrom, he will step on the running board 16, whereupon his weight, 65 by depressing said running board, will open the door 11, by raising the same. If he is about to insert articles into the furnace, he continues to walk on the running board toward the furnace, thereby holding the 70 door open, and allowing the fork 21 to be inserted. By walking backward and pulling out the fork, he retains the door in open position while withdrawing the fork from the furnace, and whenever he desires the 75 door to be closed, it is only necessary for him to step off of the running board, whereupon the door will descend by its own weight.

Having thus explained the nature of the 80 invention, and described an operative manner of constructing and using the same, although without attempting to set forth all of the forms in which it may be made, or all of the forms of its use, the following is 85 claimed:—

1. The combination with an oven, a door therefor mounted to close by gravity, and a running board pivoted at one end below the level of the door and having its free end 90 connected with said door, of a manually operable charging device for the oven capable of movement parallel with the running board which is of a length to permit an operator to take several steps thereon. 95

2. The combination with an oven, a door therefor mounted to close by gravity, a running board pivoted at one end below the level of the door and having its free end connected with said door, and means for 100 providing an adjustment between the running board and its connection with said door, of a manually operable charging device for the oven capable of movement parallel with the running board which is of a 105 length to permit an operator to take several steps thereon.

3. The combination with an oven, a door therefor mounted to close by gravity, a running board pivoted at one end below the 110

level of the door, a cable connecting the free end of the running board with said door, and a counterweight counterbalancing a portion of the weight of the door, of a manually operable charging device for the oven capable of movement with the running board, said running board being of a length to permit an operator to take several steps thereon, said running board also serving as

a partial counterbalance for the weight of 10 the door.

In testimony whereof I have hereunto set my hand.

HEINRICH TÜRK.
